M. D. Lindon

ATTORNEY.

UNITED STATES PATENT OFFICE.

MARJORIE D. LINDON, OF NEW YORK, N. Y.

LIP-STICK HOLDER OR CONTAINER.

Application filed October 6, 1927. Serial No. 224,439.

My invention relates to improvements in lipstick holders or containers.

In accordance with my invention, I provide a holder or container for receiving two lipsticks of different shades, which may be used in the day and in the night. The holder or container is compact, simple in construction, convenient in use and may be manufactured cheaply. It is small and may 10 be conveniently carried by the user.

In the accompanying drawings, forming a part of this specification, and in which like numerals are employed to designate like parts throughout the same,

15 Figure 1 is a perspective view of the holder or container closed,

Figure 2 is a similar view showing the cover elements removed,

20 Figure 3 is a central longitudinal section through the container showing one of the cover elements removed and one of the lipsticks projected to the outer position, and,

Figure 4 is a transverse section taken on line 4—4 of Figure 3.

25 The device embodies a tubular body portion 5, preferably formed of sheet metal, although any other suitable material may be used. This tubular body portion is preferably elliptical in cross section. Mounted 30 to slide within the tubular body portion 5 is a tubular lipstick holding element 6, open at both ends, and adapted to receive in its opposite ends the inner ends of the lipsticks 7 and 8, of different shades. These lipsticks 35 are frictionally held within the holding element 6. The holding element 6 is provided with a headed stud 9, screw-threaded to engage within a screw-threaded opening 10, formed in the side of the holding element 6.

40 This headed stud slides within a longitudinal slot 11, formed in the tubular body portion 5. The slot extends throughout the major portion of the length of the tubular body portion 5, and the headed stud 9 projects to the exterior of the tubular body portion 5 for engagement with the thumb or finger. The opposite ends of the tubular body portion 5 are open and the holding element 6 may be shifted longitudinally within 45 the tubular body portion 5, in opposite directions and hence the free end of either lipstick 7 or 8 may be projected beyond the tubular body portion 5, for use, as is obvious. When the holding element 6 is in

the central or intermediate position, the lipsticks 7 and 8 are covered by the tubular body portion 5.

The numeral 12 designates cover elements, closed at their outer ends and adapted for insertion upon the ends of the tubular body portion 5. When the cover elements 12 are in the closed position, their inner ends contact, and these inner ends have notches 13, to receive the shank of the headed stud 9.

55 In the use of the device, the tubular holding element 6 may be projected to the ends of the tubular body portion 5, and the lipsticks 7 and 8 inserted therein. The tubular holding element 6 may now be returned to the central or intermediate position and the cover elements 12 may be placed upon the tubular body portion 5. When the user desires to employ either lipstick 7 or 8, the adjacent cover element 12 is removed and 60 the headed stud 9 is engaged by the thumb to shift the tubular holding element 6 toward the corresponding end of the tubular body portion 5, thereby projecting the lipstick to the uncovered position, as clearly 65 shown in Figure 3. As before stated, the tubular body portion 5 is preferably formed of thin sheet metal and the cover elements also preferably formed of thin sheet metal, and are accordingly resilient. The headed stud 70 9 projects outwardly beyond the cover elements 12, and hence the user may hold one cover element 12 in one hand and exert a slight pressure thereon, which will hold the tubular body portion 5 against longitudinal 75 movement within the cover element 12. The user may then engage the headed stud 9 with the thumb of the other hand, and as this headed stud will engage the other cover element, the cover element may be shifted toward 80 the open position by the movement of the headed stud, which also advances or projects the tubular holding element to the outer position. Hence a single movement of the headed stud may be employed to remove the 85 cover element and shift the lipstick to the outer or operative position.

90 It is to be understood that the form of my device, herewith shown and described, is to be taken as a preferred example of the same, 95 and that various changes in the shape, size and arrangement of parts may be resorted to without departing from the spirit of my

invention, or the scope of the subjoined claim.

Having thus described my invention, I claim:

- 5 A holder for lipsticks of different shades or colors, comprising a tubular body portion open at both ends and having a continuous longitudinal slot extending throughout the major portion of its length, a single tubular holding element slidably mounted within the tubular body portion and having its opposite ends open to receive the lipsticks, a stud secured to the tubular holding element and extending radially through and beyond the longitudinal slot, and a pair of relatively thin flexible caps longitudinally slidably mounted upon the opposite end portions of the tubular body portion, said caps being of suitable lengths so that their inner ends substantially contact when they are in the closed position, to substantially completely cover the tubular body portion and longitudinal slot, said stud extending radially outwardly beyond said caps, the arrangement being such that one cap may be pressed 20 in the hand and clamped to the tubular body portion whereby the stud may be shifted forwardly to carry with it the other cap and the tubular holding element. 25
